(57) **CLAIM**

The ornamental design for an electronic camera, as shown and described.

DESCRIPTION

FIG. 1 is a top, rear and side perspective view of an electronic camera showing our new design;

FIG. 2 is a rear elevational view thereof;

FIG. 3 is a top plan view thereof; and,

FIG. 4 is a rear elevational view thereof, with the switch panel showing in broken line.

The portions of the electronic camera in broken lines are shown for illustrative purposes only and form no part of the claimed design.
